FILLING END PARTING MECHANISM
FOR LOOMS

John E. Smith, Greenville, S. C.

Application October 2, 1952, Serial No. 312,780

8 Claims. (Cl. 139—263)

1

This invention relates to automatic replenishing looms, and more particularly to an improved filling end parting mechanism for such looms.

In replenishing looms that operate automatically to eject a spent filling bobbin from one of the shuttle boxes and transfer a new full bobbin to the shuttle box in its place, the ejected or outgoing bobbin leaves a filling end extending from the cloth selvage that must be parted or cut to free the outgoing filling bobbin for ejection. In order to avoid leaving the remaining length of the outgoing filling end hanging loosely at the cloth selvage, it is conventional to provide a parting mechanism arranged to move adjacent the shuttle box upon transfer for parting and clamping the outgoing filling end and then withdrawing the clamped filling end away from the shuttle box so that it is held extending from the cloth selvage until cut by the temple knife.

By such an arrangement it is intended to remove the outgoing filling end substantially from the path of picking movement of the shuttle so as to prevent the filling end from being drawn into the shed to cause a cloth defect by the shuttle or as a result of the air currents induced by the shuttle and the lay movements. As a matter of fact, however, the conventional parting mechanisms heretofore commonly in use have been arranged to operate simply at the level of the shuttle box, so that when the parted outgoing filling end was clamped and withdrawn it still remained extending from the cloth selvage with a disposition substantially parallel to the shuttle flight and consequently in the path of lay as it beat up on each pick, with a resulting possibility at each pick that the lay, or the bunter thereon, or other adjacent moving loom parts, might break the filling end or pull it loose from the clamping blades.

According to the present invention an improved parting mechanism is now provided by which the clamped filling end is held extending from the cloth selvage so that it is raised above the path of the lay and other adjacent loom elements. Briefly characterized, this improved parting mechanism of the present invention comprises a pivoted mounting arrangement for the parting blade assembly on the carrier slide provided therefor, and related positioning means for supporting the pivoted parting blade assembly with the more or less level disposition that is usual as it moves to and from the replenishing shuttle box for the parting and clamping operation, but by which the parting

2

blade assembly is pivoted as it returns to its normal retracted position so that the operative end thereof is elevated to raise the filling end clamped thereby above the path of the lay and other associated loom elements. As a result, the outgoing filling end is disposed to much better advantage against breaking or pulling loose from the parting blades, and much more consistent and dependable operation of the parting mechanism is obtained.

These and other features of the improved parting mechanism of the present invention are described in detail below in connection with the accompanying drawing, in which:

15 Fig. 1 is a perspective view showing a filling end parting mechanism embodying the present invention, with the surrounding loom structure indicated fragmentarily;

15 Fig. 2 is a side elevation of the parting mechanism as would be seen from the right in Fig. 1, with the projected position of the parting blade assembly shown in full lines and the retracted position shown in dotted lines, and with related loom structure indicated in broken lines;

25 Fig. 3 is a plan view corresponding generally to Fig. 2;

Fig. 4 is a rear elevation of the parting mechanism as seen from the left in Figs. 2 and 3;

30 Fig. 5 is a fragmentary detail, partly in section, illustrating further the pivoted disposition of the parting blade assembly in retracted position; and

Fig. 6 is a similar detail showing the parting blade assembly in projected position.

35 Referring now in detail to the drawings, and more particularly at first to Fig. 1, the improved filling end parting mechanism of the present invention is shown in Fig. 1, as indicated generally by the reference numeral 10, arranged in an automatic replenishing loom of the type equipped conventionally with a transfer mechanism incorporating a reserve hopper or magazine 12 from which a stud shaft 14 projects to carry a transfer hammer 16 that is actuated by suitable connections from the lay bunter (not shown) to initiate the transfer operation when replenishment is required. The stud shaft 14 also carries a connecting linkage 18 by which reciprocating movement of the parting mechanism

40 10 is actuated from the transfer mechanism at the time of transfer to part and clamp the outgoing filling end from a shuttle such as 20 at the eye 22 of the replenishing shuttle box 24 disposed on the lay 26, all as is conventional in the art.

The stud shaft 14 additionally serves, as is usual, to support the parting mechanism 10, and for this purpose is fitted with a support bracket 28 which is preferably arranged so that the above noted reciprocating movement of the parting mechanism 10 follows an inclined path as disclosed, for example, in Burdett Patent 1,883,532. This support bracket 28 carries in turn a mounting bracket or brackets 30 on which the parting mechanism 10 is secured.

The parting mechanism 10 proper (see Figs. 2, 3 and 4) comprises a horizontal guideway 32 that is secured directly on the above mentioned mounting brackets 30, and that slidably supports a carrier 34 for reciprocation along the inclined path noted above, the carrier 34 being fitted with a pin 36 on which the previously mentioned connecting linkage 18 operates to actuate reciprocating movement of the carrier 34 from the transfer mechanism.

The carrier 34 is also fitted with a pivot stud 38 for a mounting block 40 on which fixed and movable parting and clamping blades 42 and 44 are assembled, the movable blades 44 being fitted with an opening and closing pin 46 in the usual manner. The mounting block 40 also carries an adjustable stop member 48 to determine the proper projected position of the parting and clamping blades 42 and 44 at the shuttle box 24, and is specially fitted with a cam follower pin 50 through which the mounting block 40, and the parting and clamping blades 42 and 44 assembled thereon, are pivoted to an elevated position for raising a clamped filling end above the moving loom parts as previously mentioned.

The pivoting movement of the mounting block 40 and blades 42 and 44 is actuated from an elevating cam 52 disposed below the mounting block 40 on a bracket 54 extending from a mounting point on the slide 32. This elevating cam 52 terminates rearwardly in a rounded toe portion as at 52' so that the mounting block follower pin 50 will ride on and off of it as the carrier 34 is reciprocated at the time of transfer. In the normal retracted position for the parting and clamping blades 42 and 44 (see Fig. 5), the follower pin 50 rides on top of the elevating cam 52 and maintains the mounting block 40 and blades 42 and 44 pivoted to a raised position, as shown. At transfer, however, as the carrier 34 moves rearwardly toward the shuttle box 24, the follower pin 50 rides off the toe 52' of cam 52 allowing the mounting block 40 and blades 42 and 44 thereon to assume by the action of gravity a more or less level disposition such as is usual, the carrier 34 being fitted with a stop pin 56 for supporting the mounting block 40 and blades 42 and 44 with the proper level disposition.

The opening and closing movement of the clamping blades 42 and 44 is actuated in the usual manner by trip cams 58 and 60, the opening trip cam 58 being mounted beside the elevating cam 52 on the bracket 54 and the closing trip cam 60 on an auxiliary bracket arm 62 extending therefrom. By usual manner of actuation for the clamping blades 42 and 44 it is meant that the opening cam 58 engages the pin 46 to open the movable blades 44 upon rearward movement of the carrier 34 to projected position, while the closing cam 60 engages the pin 46 to close the movable blades 44 upon return movement to retracted position.

The present invention has been described above in detail for purposes of illustration only and

is not intended to be limited to this description or otherwise except as defined in the appended claims.

I claim:

- 5 1. A filling end parting mechanism for replenishing looms, said mechanism comprising a filling end parter, a carrier pivotally supporting said parter, and cam means for pivoting said parter to an elevated position with respect to said carrier when retracted while allowing said parter to be lowered to a normal operative position upon movement to part an outgoing filling end at the time of transfer.
- 15 2. A filling end parting mechanism for replenishing looms, said mechanism comprising a filling end parter, a carrier pivotally supporting said parter, said carrier being operatively associated in said loom to move said parter between a normal retracted position and a projected operative position at which an outgoing filling thread may be parted at the time of transfer, and cam means for elevating said pivoted parter when in said retracted position while allowing said parter to be lowered during movement to said operative position.
- 20 3. In a replenishing loom, the combination with an outgoing filling end parter, and means operating said parter to move between a normal retracted position and a projected operative position for parting an outgoing filling end at said projected position upon transfer and for clamping and holding the parted filling end from the cloth selvage while returning to said retracted position and until a subsequent transfer occurs, of means for pivotally supporting said parter for raising and lowering the parting and clamping end thereof during said movement, and cam means disposed for raising said parter end at said retracted position while allowing said end to be lowered during movement to said operative position.
- 25 4. In a replenishing loom having a transfer mechanism and a filling end parting mechanism operatively associated therewith for moving a parter incorporated in said latter mechanism between a normal retracted position and a projected operative position and for operating said parter to part an outgoing filling end at said projected position upon transfer and for clamping and holding the parted filling end from the cloth selvage while returning to said retracted position and until a subsequent transfer occurs, the improvement which comprises a pivot support for said parter allowing it to be raised and lowered during said movement, and cam means for maintaining said parter raised at said retracted position while allowing said parter to be lowered during movement to said operative position.
- 30 5. A filling end parting mechanism for a replenishing loom, said mechanism comprising a support associated with the transfer mechanism and disposed adjacent the replenishing shuttle box of said loom, a guideway mounted on said support, a carrier slidably disposed in said guideway, a filling end parter pivoted on said carrier, means connecting said carrier for actuation from said transfer mechanism to move said parter between a normal retracted position on said support and a projected operative position at said shuttle box upon transfer, a first cam means mounted on said support for opening said parter during movement to said projected position, a second cam means mounted on said support for closing said parter at said shuttle box upon re-

turn movement to said retracted position, and a third cam means mounted on said support for pivoting said parter to an elevated position at said retracted position while allowing said parter to be lowered during movement to and from said projected position.

6. A filling end parting mechanism for a replenishing loom, said mechanism comprising a support associated with the transfer mechanism and disposed adjacent the replenishing shuttle box of said loom, a guideway mounted on said support, a carrier slidably disposed in said guideway, a filling end parter pivoted on said carrier and incorporating relatively fixed and movable parting and clamping blades, means connecting said carrier for actuation from said transfer mechanism to move said parter between a normal retracted position on said support and a projected operative position at said shuttle box for parting an outgoing filling end upon transfer, means for opening said parter blades during movement to said projected position, means for closing said parter at said shuttle box upon return movement to said retracted position, and means for pivoting said parter to an elevated position at said retracted position.

7. A filling end parting mechanism for a replenishing loom, said mechanism comprising a support associated with the transfer mechanism and disposed adjacent the replenishing shuttle box of said loom, a horizontal guideway on said support, a carrier slidably disposed for reciprocation in said guideway, a filling end parter pivoted on said carrier, means connecting said carrier for actuating reciprocation thereof from said transfer mechanism to move said pivoted parter between a normal retracted position on said support and a projected operative position at said shuttle box for parting an outgoing filling end upon transfer, a stop element on said carrier supporting said pivoted parter with a substantial level position during movement to and from

said projected position, and cam means on said support for pivoting said parter to an elevated disposition at said retracted position.

8. A filling end parting mechanism for a replenishing loom, said mechanism comprising a support associated with the transfer mechanism and disposed adjacent the replenishing shuttle box of said loom, a horizontal guideway on said support, a carrier slidably disposed for reciprocation in said guideway, a filling end parter pivoted on said carrier and incorporating relatively fixed and movable parting and clamping blades, means connecting said carrier for actuating reciprocation thereof from said transfer mechanism to move said pivoted parter between a normal retracted position on said support and a projected operative position at said shuttle box for parting an outgoing filling end upon transfer, a stop element on said carrier supporting said pivoted parter with a lowered position substantially aligned horizontally with said guideway during movement to and from said projected position, means for opening said parter blades during movement to said projected position, means for closing said parter blades at said shuttle box upon return movement to said retracted position and thereby parting and clamping said outgoing filling end, and cam means on said support for pivoting said parter to elevate the operative end of said closed parting blades at said retracted position and thereby hold the clamped filling end extending from the cloth selvage raised above the path of the lay and other adjacent moving loom elements.
